UNITED STATES PATENT OFFICE.

WILLIAM H. DOBLE, OF QUINCY, MASSACHUSETTS, ASSIGNOR OF ONE-FOURTH TO PNEUMATIC SCALE CORPORATION, LIMITED, OF QUINCY, MASSACHUSETTS, A CORPORATION OF MAINE.

PANEL FOR BOXES.

1,228,760.

Specification of Letters Patent.

Patented June 5, 1917.

Application filed July 9, 1915. Serial No. 38,890.

To all whom it may concern:

Be it known that I, WILLIAM H. DOBLE, citizen of the United States, residing at Quincy, county of Norfolk, State of Massachusetts, have invented a certain new and useful Improvement in Panels for Boxes, of which the following is a specification, reference being had therein to the accompanying drawings.

10 The invention relates to a box panel having an inner and outer wall spaced apart from each other, being specially intended for use in a box or shipping case of the folding variety in which the panel forming one side of the box is hinged to a panel forming another side of the box, and by the term "side" is meant any one of the four sides or the top or bottom of the box.

15 The invention is especially adapted for a metal box, although it will be obvious that other material may be employed, and also that a panel constructed in accordance with the invention may be employed in construction of boxes which are not of the knock-down or folding variety.

20 The present invention is an improvement on the box panel shown in Patent No. 941,013, granted to Doble and Wheaton November 23, 1909, in which the panel has a double wall comprised of two parallel plates spaced apart from each other and has an intermediate corrugated plate whose corrugations contact alternately with said first two plates.

25 The present invention comprises an inner and an outer plate spaced apart from each other forming respectively the inner and outer faces of the panel, and a plurality of corrugated plates side by side between the said inner and outer plates, one corrugated plate having corrugations which alternately engage with the inner face plate of the panel and with another corrugated plate, said other corrugated plate being in engagement alternately with the other face plate of the panel and with said first corrugated plate, and said two corrugated plates having portions which engage with each other alternately with the portions which engage with the face plate. By "corrugated plate" is meant broadly a plate of zig zag form.

30 The invention will be fully understood from the following description when taken in connection with the accompanying draw-

ings and the novel features thereof will be pointed out and clearly defined in the claims at the close of the specification.

In the drawings,—Figure 1 is a plan view partly broken away of a panel embodying the invention.

60 Fig. 2 is a section on line 2—2 of Fig. 1.

Fig. 3 is a section on line 3—3 of Fig. 1.

Fig. 4 is a modification of the corrugated plate which is made in sections instead of continuous.

65 Fig. 5 is a sectional view at right angles to Fig. 4.

Fig. 6 shows an additional plate interposed between two corrugated plates.

Referring now to the drawings,—1 represents one of the face plates of the panel and 2 represents the other face plate, said two face plates being for convenience termed respectively the outer and the inner face plates, meaning by the term "outer face plate" the one which will be the outside plate of the panel when assembled with other panels to form a box and the "inner plate" being the one which will form the inside face of the panel of a finished box. These two 70 plates 1 and 2 are spaced some distance apart from each other and interposed between said plates 1 and 2 are two corrugated plates 3, 4, each of which has corrugations extending transversely thereof, the plate 3 having in one plane elevated portions 3^a which contact with the inner face of the plate 1 and depressed portions 3^b in another plane which contact with the depressed portions 4^b of the plate 4, said plate 75 4 having elevated portions 4^a in one plane which engage with the inner face of the plate 2. In saying that the corrugations extend transversely of the plates, it is meant that they extend substantially from one edge 80 to the opposite edge of the corrugated plate whether longitudinally or widthwise. Thus the elevated and depressed portions 3^a and 3^b of the corrugated plate 3 respectively engage alternately with the face plate 1 and the corrugated plate 4, and the alternating elevated and depressed portions of the corrugated plate 4 respectively engage alternately with the face plate 2 and corrugated plate 3. The corrugated plates brace and 85 stiffen each other and also the inner and outer face plates of the entire panel.

90 95 100 105 Preferably these corrugations form a se-

ries of troughs extending the entire length or width, as the case may be, of the corrugated plate, with flat surfaces which contact with the face plates and with the companion 5 corrugated plate. Preferably also the corrugations of the plate 3 extend at right angles to the corrugations of the plate 4 so that, as shown in Fig. 2 the bottom of the trough or the corrugation of the plate 3 will

10 not only rest upon the depressed portions 4^b of the corrugated plate 4 but will also bridge across the space between said depressed portions 4^b of the plate 4 and also the depressed portions 4^b of the said plate 4 will contact 15 with the depressed portions 3^b of the plate and will bridge across the space between said depressed portions 3^b as shown in Fig. 3.

The said corrugated plates 3, 4 and the face plates 1 and 2 are preferably all secured 20 together at their respective contact points to prevent their becoming displaced and the preferred method of thus uniting them is by welding.

Preferably the se corrugated plates do not 25 extend quite to the edges of the inner and outer plates, thus leaving at the edges a place for the insertion of channel plates to close the open space at the edge. For instance, on one edge, as in Fig. 2, a U-shaped 30 channel plate 5 is inserted which extends across the entire end or side of the panel and in another edge is inserted a channel plate 6 which also closes that edge and is formed with a series of eye portions 7 adapted to 35 receive a hinge pin to connect the said panel with another panel having a series of eyes which fit in between the eyes 7.

In the modification shown in Fig. 4 instead of having two continuous corrugated 40 plates each bracing the other they are made in sections. For instance, in place of the integral corrugated plate 4 shown in Fig. 1 there are employed a series of plates 8 shaped something like the letter Z alternat- 45 ing with reversely turned Z-shaped plates each having a portion 8^a which bears against one of the sections 9 of a corresponding corrugated plate and another portion 8^b which bears against the face plate 2, and an in- 50 clined connecting portion 8^c. Each one of these sections 8 and 9 extends crosswise of the panel in one direction, the sections 8 and 9 being at right angles to each other in the same way that the corrugated plates 3 and 55 4 are placed at right angles to each other so that each one of the sections 9 will bear against a series of sections 8 and each one of the sections 8 will bear against a series of sections 9.

60 It is not essential that the corrugated plates 3 and 4 should be in actual contact with each other. There may be, if desired, an additional plate interposed between said plates 3 and 4, as shown in Fig. 6, in which 65 the plate 10 is interposed so that the cor-

rugated plates 3 and 4 instead of coming directly in contact with each other come in contact with the said interposed plate, and in the claims in which it is stated that the said corrugated plates engage each other 70 it is intended to use that expression broadly to cover either direct physical contact with each other or through the medium of an interposed plate.

What I claim is:

1. A box panel consisting of two metallic face plates spaced apart from each other, two metallic corrugated plates inserted between said face plates, one of said corrugated plates having portions which engage with one of said face plates and the other of said corrugated plates having portions which engage with the other of said face plates and each of said corrugated plates having other portions which engage 80 with portions of said other corrugated plate, the engaging portions of said plates being welded together at the points of contact.

2. A box panel consisting of two metallic face plates spaced apart from each other, two metallic corrugated plates inserted between said face plates, the said corrugated plates being corrugated in such manner as to have a series of alternating broad flat faced depressions and elevations, thus forming a series of flat faces separated from each other in one plane and another series of flat faces separated from each other in another plane, the two sets of flat faces being in planes parallel with each other, one set of the flat faces of one of the corrugated plates engaging one of said face plates, one set of the flat faces of the other corrugated plate engaging with the other face plate, and the second set of flat faces of the first 90 of said corrugated plates engaging with the second set of flat faces of the second corrugated plate, the contacting faces of said corrugated plates and face plates all being welded together.

3. A box panel consisting of three or more metallic plates superposed upon each other, the intermediate plates having corrugations formed in such manner as to form flat topped and flat bottomed depressions, the flat contacting faces of all of said plates being welded together, thereby uniting all of said members into one integral panel.

4. A box panel consisting of two metallic face plates spaced apart from each other, two metallic corrugated plates inserted between said face plates, said corrugated plates being corrugated in such manner as to each have a series of alternating broad flat faced depressions and elevations which extend 115 transversely thereof, thus forming in each corrugated plate a series of flat faces separated from each other in one plane and another series of flat faces separated from each other in another plane, the two sets of flat 120 faces being welded together.

faces being in planes parallel with each other, the said corrugated plates being arranged so that the corrugations of one plate extend at right angles to those of the other 5 corrugated plate, the contiguous flat faces of the two corrugated plates being welded together where they cross each other, and the two face plates also being welded to the

contiguous flat faces of the corrugated plates.

10

In testimony whereof I affix my signature, in presence of two witnesses.

WILLIAM H. DOBLE.
